Primary Examiner — Michael A. Pratt*Assistant Examiner* — Adam C Mager(74) *Attorney, Agent, or Firm* — McCormick, Paulding & Huber PLLC(57) **CLAIM**

The ornamental design for a hydrofoil shield, as shown and described.

DESCRIPTION

FIG. 1 is a front top, and right side perspective view of a hydrofoil shield comprising a new, original and ornamental design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the hydrofoil shield that form no part of the claimed design.
